COPING BLOCK FOR SWIMMING POOLS

John Kautz, San Mateo, Calif.

Application October 20, 1955, Serial No. 38,479

Term of patent 14 years

(Cl. D18—2)

Fig. 1 is a perspective view of a coping block for swimming pools showing my new design.

Fig. 2 is a plan view of the coping block shown in Fig. 1.

Fig. 3 is an end elevational view of the coping block shown in Figs. 1 and 2.

I claim:

The ornamental design for a coping block for swimming pools as shown.
